UNITED STATES PATENT OFFICE.

EDWIN C. SHAW, OF AKRON, OHIO, ASSIGNOR, BY MESNE ASSIGNMENTS, TO THE B. F. GOODRICH COMPANY, A CORPORATION OF NEW YORK.

TOOL.

1,081,336.

Specification of Letters Patent. Patented Dec. 16, 1913.

Application filed May 2, 1910. Serial No. 558,975.

To all whom it may concern:

Be it known that I, EDWIN C. SHAW, a citizen of the United States, residing in Akron, county of Summit, and State of Ohio, have invented certain new and useful Improvements in Tools, of which the following is a specification.

My invention relates to tools designed primarily for facilitating the performance 10 of many of the operations necessary in the manipulation of various well known forms of detachable pneumatic or other resilient tires and detachable or separable rims. Tools of this class are commonly known as 15 "tire tools," although they are used not only for detaching the tire itself from the rim, but are designed to be used for assembling the various parts of a separable rim, for example, as illustrated in the drawings accompanying this specification, or for the 20 manipulation of certain forms of demountable rims.

In the accompanying drawings, which form a part of this specification, Figure 1 25 is a perspective view of a section of a tire and rim and of my improved tool, showing its mode of operation when used to draw together the split flange of a two part separable or so-called "quick-detachable" rim; Fig. 2 is a view showing the two parts of 30 the tool separated; Fig. 3 is a detail view partly in section of the end of one of the tool parts illustrating the construction of the reversible plug; Fig. 4 is a cross section 35 of a portion of a rim and detachable flange showing a mode of using my device for removing the detachable flange.

Referring to the drawings in detail, the tool comprises a pair of crossed bars 1 and 40 2 pivoted together in any suitable manner as by means of a pin 3 projecting from one of the bars through an opening 4 in the other bar. The pin 3 preferably has a T-shaped head 5 which may be passed through 45 the opening 4 when the bars are turned to such a position that the longer axis of the head corresponds with the greatest diameter of the opening 4, the head preventing the separation of the bars when they are 50 turned to any other position. The portion of the bar 2 about the opening 4 is preferably recessed, as indicated at 6, to receive the T-shaped head. The shoulder arms 7 of the bars are preferably turned outwardly 55 beyond the point where the bars are piv-

oted, the ends of these arms being formed into internally threaded eyes 8. Threaded plugs 9 screw into these eyes, each plug being provided with a faced portion 10, or other suitable means, by which it may be 60 turned when being screwed into its eye, or withdrawn therefrom.

Projecting from the ends of the plug are pins or studs 11 and 12, preferably of different characteristics, such as diameter, as 65 shown in the drawings, or it may be of different lengths or shapes, in order to make them suitable to engage different types of rims or different parts of the same rim. As shown in the drawings, the pins have dif- 70 ferent diameters, Figs. 1 and 2 showing the plugs inserted with the small pins 12 projecting in such manner as to be engaged with holes in the ends of the split tire retaining flange 20 on the rim 21. Fig. 3 75 shows how the plugs may be reversed to bring the pins 11 of larger diameter into operative position, thereby rendering the tool suitable for use with a rim in which the engaging sockets are larger. 80

The long arms 13 of the bars 1 and 2 serve as handles when the tool is being used, as shown in Fig. 1, one or both of these arms preferably terminating in sharpened portions 14 adapted to be inserted in a notch 85 15 in the rim flange 20 to detach the same, as indicated in Fig. 4, or to be used to lift a tire bead over the flange of a one piece rim, or in any other suitable manner. When the tool is used in this manner the bars are 90 preferably separated, as indicated in Fig. 2, two tools or levers being thus provided. This is particularly desirable when using the tool to apply a tire to the ordinary one piece clencher rim as a pair of levers are 95 necessary satisfactorily to perform that operation.

Having thus described a preferred embodiment of my invention, but without desiring to limit myself to the precise details 100 set forth and illustrated, I claim:

1. A tire tool comprising a pair of crossed bars pivoted together, one arm of each bar having projecting therefrom oppositely disposed studs of different diameters. 105

2. A tire tool comprising a pair of members pivoted together, each of said members carrying at one end a reversible plug having a stud projecting from each end thereof. 110

3. A tire tool comprising a bar having at one end thereof an eye and a reversible plug mounted in said eye, said plug having a stud projecting from each end thereof.
4. A tire tool comprising a pair of bars pivoted together, each bar having at one end thereof an internally threaded eye, a

reversible threaded plug screwed into each eye, and a stud projecting from each end of said plug.

EDWIN C. SHAW.
